(57) **CLAIM**

The ornamental design for a device for carrying babies, as shown and described.

DESCRIPTION

FIG. 1 is a front view of a device for carrying babies showing my new design;

FIG. 2 a right side perspective view thereof; and,

FIG. 3 is a left side perspective view thereof.

The portions shown in broken lines form no part of the claimed design.

1 Claim, 3 Drawing Sheets

FIG. 1

FIG. 2
